UNITED STATES PATENT OFFICE

120,542

DESIGN FOR A CASING FOR A COMBINED MILK CAN WASHER, STERILIZER, AND DRIER

Willard S. Campbell, Hampshire, Ill.

Application February 21, 1940, Serial No. 90,409

Term of patent 7 years

To all whom it may concern:

Be it known that I, Willard S. Campbell, a citizen of the United States of America, residing at 10 Park Avenue, Hampshire, Illinois, have invented a new, original, and ornamental Design for a Casing for a Combined Milk Can Washer, Sterilizer, and Drier, of which the following is a specification, reference being had to the accompanying drawing, forming a part thereof.

Fig. 1 is a perspective view of a casing for a combined milk can washer, sterilizer, and drier showing my new design which is the same on

both of its side portions; Fig. 2 is an elevational view of the end portion not shown in Fig. 1, Fig. 3 is a top plan view thereof, and Fig. 4 is an enlarged detailed vertical sectional view as shown on line 4—4 of Fig. 1, Figs. 2 and 3 are drawn on a slightly smaller scale than Fig. 1.

I claim:

The ornamental design for a casing for a combined milk can washer, sterilizer, and drier, substantially as shown and described.

WILLARD S. CAMPBELL.
